[57] CLAIM

The ornamental design for a magnetic fender cover, as shown and described.

DESCRIPTION

FIG. 1 is a perspective view of a magnetic fender cover, showing my new design;

FIG. 2 is an enlarged front elevational view thereof;

FIG. 3 is an enlarged rear elevational view thereof;

FIG. 4 is a further enlarged top plan view thereof;

FIG. 5 is a further enlarged bottom plan view thereof;

FIG. 6 is a further enlarged left side view thereof; and,

FIG. 7 is a further enlarged right side view thereof.

The magnetic fender cover is shown broken away in FIGS. 4-7 for ease of illustration.
